UNITED STATES PATENT OFFICE.

ADOLPH G. LOTTER, OF MILWAUKEE, WISCONSIN, ASSIGNOR TO H. C. MILLER CO.,
OF MILWAUKEE, WISCONSIN.

UNIT FOR HOLDING THE LEAVES IN A VISIBLE-RECORD SYSTEM.

Application filed March 14, 1927. Serial No. 175,150.

This invention relates to a unit for holding the leaves in a visible record system.

This invention is an improvement over that disclosed in the copending applications of Henry C. Miller for visible record system, filed December 10, 1925, Serial No. 74,523; and unit for holding the leaves in a visible record system, filed March 29, 1926, Serial No. 98,399; and it has in general the same objects set forth in such applications.

Further objects are to provide a unit for holding the leaves in a visible record system in which a pair of parallel bars are provided with curved impaling prongs which are adapted to contact and to form continuous rings for the reception of perforated sheets.

Further objects are to provide a unit for a visible record system in which the leaf rests or parallel bars are so mounted that they may be separated and may be shifted longitudinally to individually or collectively shift the sheets, and to permit the insertion or removal of sheets.

Further objects are to provide a device in which there is no relative folding of the parts, but in which the bars or leaf rests are separated by direct outward motion, in which the motions of separation and longitudinal shifting are distinct and are independently performed.

Further objects are to provide a single locking means for simultaneous locking against both separation and longitudinal shifting and to provide a locking means with cam surfaces to draw the ends of the prongs tightly against each other, and to provide composite bars or leaf rests which consist of a main body portion guided for parallel outward motion and for longitudinal shifting motion, and plates mounted above the body portion of the bars and cooperating with the locking means so that the plates bear against the base of the prongs and force the prongs towards each other into intimate binding relation.

Further objects are to provide a novel form of unit for visible record system in which the prongs are provided with interengaging means at their ends to rigidly

lock the ends of adjacent prongs against relative motion when the device is closed, so that not only are the prongs locked at their bases, but also are locked at their contacting free ends.

An embodiment of the invention is shown in the accompanying drawings in which:

Figure 1 is a plan view of the device with parts broken away;

Figure 2 is a view corresponding to Figure 1 showing the leaf rests or parallel bars separated;

Figure 3 is a view corresponding to Figure 2 showing the bars moved towards each other after longitudinal shifting;

Figure 4 is a plan view of the structure shown in Figure 2 with parts of the device removed to show the lower mechanism;

Figure 5 is a transverse sectional view through the device;

Figure 6 is a longitudinal sectional view on the line 6—6 of Figure 5.

Referring to the drawings, it will be seen that the device comprises a main base plate 1 and a sub-base plate 2. The sub-base plate 2 is more of the nature of a finishing or protecting shell, as may be most clearly seen from Figures 5 and 6. The main base plate 1 has a pair of main crossed levers 3 pivoted thereto, as indicated at 4, and shown most clearly in Figures 4 and 6. These levers 3 are provided with slots 5 in their outer ends and these slots engage pins 6 carried by the parallel bars 7, as most clearly shown in Figure 4. The bars 7 constitute portions of leaf rests. These leaf rests are composite structures, as will be described hereinafter, and are adapted to be moved outwardly by a direct motion into the position shown in Figure 4. Two pairs of links 8 are each pivoted together at their outer ends, as indicated at 9, and at their inner ends are pivoted, as indicated at 10', to an intermediate portion of the levers 3. The pivot pins 9 of the levers 8 ride in slots 10 formed

in the base plate 1, as may be seen from Figure 6, and partly from Figure 4. This mechanism insures parallel motion for the leaf rests. The outer ends of the leaf rests are guided by means of inwardly turned 100

flanges 11 and 12 formed integral with the base plate, as shown most clearly in Figures 1, 2, 3, and 6. One of the flanges, 12, for instance, is provided with notches 13 adapted 5 to receive the studs 14 and 15 carried by the leaf rests. The stud 15 is adapted to enter either the notch 13 or to pass on the outer side of the finger 14', as shown in Figure 3.

It is to be noted that the bars 7 carry 10 plates 16 and 17. The plate 17 is rigidly secured to the corresponding bar 7, whereas the plate 16 is slidably guided upon the bar 7 by means of pins 18 rigid with the bar 7 and cooperating with slots 19 formed in the 15 plate 16. The plates 16 and 17 carry prongs 20 and 21, as shown in Figures 1 to 3 and 5, the prongs being removed in Figure 4 for the sake of clearness.

Further, it is to be noted from Figures 1, 20 2, 3, and 5, that auxiliary plates 22 are positioned above the plates 16 and 17 and are provided with apertures through which the prongs 20 and 21 pass, as may be seen from Figure 5.

25 Slot and pin connections are provided between the plates 16 and 17 and the plates 22, as indicated by the reference character 22', Figure 2.

From the mechanism thus far described, it 30 is apparent that the leaf rests or parallel bars may be pulled apart from the position shown in Figure 1 by grasping the studs or manipulating pins 14 and 15. The parts may be drawn directly apart, as stated, and 35 if it is desired to shift certain of the sheets the pin 15 may be pushed longitudinally to thus slide the prongs 20 into the position shown in Figure 2. Thereafter, the parts are moved towards each other to the position 40 shown in Figure 3 with the pin 15 on the other side of the finger 14' of the flange 12. When the parts are in this position, it is apparent that rocking of the sheets 24 over from one set of prongs to the other will 45 cause the prongs to be positioned in other of the apertures 23 of the sheets (see Figure 1) from those previously occupied, it being noted that the apertures 23 are arranged at the positions of the prongs and also intermediate such positions.

50 After the sheets have been rocked as desired, the parts are separated into the position shown in Figure 2, and the prongs 20 are shifted downwardly into their original 55 position and thereafter the two portions are slid towards each other to again assume the position shown in Figure 1.

Means are provided for simultaneously locking the parts in closed position against 60 both direct separation and longitudinal shifting. This means may comprise a locking strip 25 which is provided with a manipulating thumb piece 26 and is provided with slots 27 which are guided by pins 28 65 passing upwardly from the base plate 1, and

also by an extension of the central pivot 4 as shown most clearly in Figure 6. This locking bar is provided with raised portions 29 and also with cutout portions providing cam faces 30 adjacent these raised portions. 70 These cam faces define notches, and it is to be noted particularly from reference to Figure 2, that the cam faces are divergent at their outer portions and parallel at their inner portions. These cam faces engage upwardly turned lips 31 formed integrally with the plates 22, as shown most clearly in Figure 5. As shown in Figures 1, 2, and 3, a pair of these upwardly turned lips 31 are provided adjacent each end of the device and 80 a corresponding locking notch with cam faces 30 is also provided at these points. Thus, the sliding of the locking bar 25 upwardly in the positions shown in Figures 1 and 6, causes simultaneous engagement of the two pairs of ears 31 and consequently rigidly locks the parts against both lateral separation and longitudinal motion, it being noted that the pin 15 is positioned within the notch 13 and consequently when the parts are 90 locked in this position no longitudinal shifting can occur.

It is to be noted further that the parallel motion mechanism causes an easy separation of the parts when the pins 14 and 15 are 95 manipulated, and that no wedging or tilting can occur.

Further, it is to be noted that very simple means have been provided for effectively and positively locking the parts simultaneously against separation and longitudinal motion.

It is to be noted further particularly from Figure 5 that when the cam faces 30 engage the lips 31 that they tend to slide the plates 22 inwardly towards each other and, consequently, force the plates against the bases of the prongs 20 and 21 and aid in tightly binding the ends of the prongs against each other.

105 It is to be noted from Figure 5 that one of the prongs of each pair is provided with a pin 32 which fits within an aperture 33 formed in the other prong. If desired, the apertures and pins may alternate, as shown 110 in Figures 2 and 3, for successive pairs of prongs.

Further, as shown in Figures 1, 2, and 3, it is preferable to provide the prongs with slanting outer faces which contact, as shown 115 in Figure 1, when the device is closed.

It is also to be noted that this unit may be fastened upon a table, if desired, or else 120 may be provided with hinge members 34 (see Figures 1, 3, and 5) which are adapted to hingedly receive covers 35.

125 It is to be noted particularly from Figures 1, 2, 3, and 6 that the locking bar 25 is provided with upturned lugs 36 adjacent the slot 27 nearest to the thumb piece 130

or handle 26. These upturned lugs cooperate with the head of the pin 28 and may be positioned on either side of such head by depressing the thumb piece end of the bar 5 and sliding the bar longitudinally; that is to say transversely of the entire device. The locking bar is held pressed upwardly towards the head of the rivet by means of a spring 37 which bears against a washer 38 (see Figure 10 4) located beneath the bar and surrounding the rivet 28.

It is thus apparent that the bar is locked against inadvertent motion by this simple mechanism.

15 It will be seen that a novel form of unit for a visible record system has been provided by this invention in which the composite prong-carrying leaf rests may be simultaneously locked against separation and longitudinal motion by a single manipulation of the locking member.

Further, it is to be noted that this locking member locks the leaf rests at widely separated points and thus provides a very 25 secure lock.

It is to be noted further that the cooperating or interlocking outer ends of the prongs maintain correct alignment of the free ends of the prongs when the device is closed, 30 and prevents inadvertent distortion or separation of these ends. Thus, as the prongs are held both at their outer and inner ends, it is apparent that a very rigid and secure device is provided.

35 Although the invention has been described in considerable detail, such description is intended as illustrative rather than limiting, as the invention may be variously embodied and as the scope of such invention 40 is to be determined as claimed.

I claim:

1. A unit for a record system comprising a base plate, a pair of parallel bars upon said base plate, impaling prongs carried by 45 said bars, parallel motion mechanism connecting said bars and base plate, whereby said bars may be separated by a direct lateral movement, one of said bars being adapted for also being longitudinally shifted, and a single locking means for simultaneously locking said bars against relative motion, said locking means locking each of said bars at widely separated points.

2. A unit for a record system comprising 55 a base plate, a bar adjacent each side of said base plate, curved impaling prongs carried by said bars and having contacting ends and forming continuous rings from one bar to the other bar, means guiding 60 said bars upon the base plate for lateral separation, one of said bars being adapted also for longitudinal shifting motion relative to the other bar, and means for simultaneously locking said bars against separation and longitudinal shifting, said lock-

ing means including a part movable longitudinally over said base plate.

3. A unit for a record system comprising a base plate, a bar adjacent each side of said base plate, curved impaling prongs carried by 70 said bars and having contacting ends and forming continuous rings from one bar to the other bar, means guiding said bars upon the base plate for lateral separation, one of said bars being adapted also for longitudinal shifting motion relative to the other bar, and means for simultaneously locking said bars against separation and longitudinal shifting, said locking means including a part movable longitudinally over 75 said base plate and engaging said bars at widely spaced points.

4. A unit for a record system comprising a base plate, a bar adjacent each side of said base plate, said bars having curved impaling 80 prongs having contacting ends, means for guiding said bars upon said base, whereby said bars may be separated, each of said bars being composite and composed of a lower member and an upper member with 85 the upper member engaging the base of said prongs, and locking means for locking said bars against relative motion, said locking means engaging the upper member of each bar and drawing said members towards 90 each other, whereby the ends of the prongs are tightly forced together.

5. A unit for a record system comprising a base plate, a pair of parallel bars upon said base plate, impaling prongs carried by 100 said bars, parallel motion mechanism connecting said bars and base plate, whereby said bars may be separated by a direct lateral movement, one of said bars being adapted for also being longitudinally shifted, 105 and a single locking means for simultaneously locking said bars against relative motion, said locking means locking each of said bars at widely separated points, said locking means being cammed to tightly 110 force the ends of the prongs into contact with each other.

6. A unit for a record system comprising a base plate, a pair of bars upon said base plate and each bar having a series of prongs 115 contacting at their ends with the prongs of the other pair and forming rings, means for guiding said bars upon said base, whereby said bars may be laterally separated, means for longitudinally guiding one of said bars, 120 whereby such bar may be longitudinally shifted with respect to the other bar, means for locking said bars against longitudinal and lateral motion, said prongs of each ring having interlocking means at their ends to 125 prevent relative motion of such ends when the ends are in contact.

7. A unit for a record system comprising a base plate, a pair of bars upon said base plate and each bar having a series of prongs 130

contacting at their ends with the prongs of the other pair and forming rings, means for guiding said bars upon said base, whereby said bars may be laterally separated, means for longitudinally guiding one of said bars, whereby such bar may be longitudinally shifted with respect to the other bar, means for locking said bars against longitudinal and lateral motion, one prong of each ring 10 having a pin projecting from its end and the other prong of the ring having a hole in its end for the reception of said pin.

8. A unit for a record system comprising a base plate, a pair of parallel bars upon said base plate, impaling prongs carried by said bars, parallel motion mechanism connecting said bars and base plate, whereby said bars may be separated by a direct lateral movement, one of said bars being 15 adapted for also being longitudinally shifted, a single locking means for simultaneously locking said bars against relative motion, and a second locking means for locking said first-mentioned locking means 20 against motion.

In testimony that I claim the foregoing I have hereunto set my hand at Milwaukee, in the county of Milwaukee and State of Wisconsin.
